US00D971977S

(12) **United States Design Patent** (10) **Patent No.:** **US D971,977 S**
(45) **Date of Patent:** **** Dec. 6, 2022**

(54) **TRAVEL MOTOR**

(71) Applicant: **Shenzhen Seauto Technology Co., Ltd.**, Shenzhen (CN)

(72) Inventor: **Zhuoming Deng**, Shenzhen (CN)

(73) Assignee: **Shenzhen Seauto Technology Co., Ltd.**, Shenzhen (CN)

(**) Term: **15 Years**

(21) Appl. No.: **29/830,312**

(22) Filed: **Mar. 11, 2022**

(51) LOC (13) Cl. **15-99**

(52) U.S. Cl.

USPC **D15/148**; D13/112

(57) **CLAIM**

The ornamental design for a travel motor, as shown and described.

DESCRIPTION

FIG. 1 is a front, right and top perspective view of a travel motor, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a screw rod; and,

FIG. 10 is a partial enlarged view of an area labeled 10 in FIG. 4 comprising a rear side of a screw rod.

The broken lines in the drawings depict portions of the travel motor that form no part of the claimed design. In addition, the dot-dash broken lines in the drawings illustrate enlarged portion of the design.

1 Claim, 10 Drawing Sheets
